UNITED STATES PATENT OFFICE.

JOHN H. GOODFELLOW, OF BUFFALO, NEW YORK.

BOILER-TUBE CLEANER.

Application filed November 3, 1919. Serial No. 335,266.

To all whom it may concern:

Be it known that I, JOHN H. GOODFELLOW, citizen of the United States, and resident of the city of Buffalo, in the county of Erie 5 and State of New York, have invented certain new and useful Improvements in Boiler-Tube Cleaners, of which the following is a specification, reference being had to the accompanying drawings.

10 This invention relates to a boiler tube cleaner which utilizes steam and air as the cleaning medium.

The principal object of this invention is to provide a cleaner of this character which 15 is simple and light in construction; which is durable and efficient in operation; and which can be manufactured at a low cost.

Another object is to so construct the cleaner that a whirling or cyclonic action 20 is imparted to the air and steam whereby the tubes are quickly and thoroughly cleaned in a minimum period of time.

In the accompanying drawings:

25 Figure 1 is a side elevation of a boiler tube cleaner embodying my improvements.

Figure 2 is a longitudinal section thereof.

Figure 3 is a front view thereof.

Figure 4 is a rear view thereof.

30 Figure 5 is a vertical transverse section on line 5—5, Figure 2.

Figure 6 is an enlarged rear view of the nozzle detached from the cleaner body.

Similar characters of reference indicate 35 corresponding parts throughout the several views.

10 indicates the body or head of the cleaner which is preferably hollow and open at both ends and constructed of cast metal, such as iron. It is preferably round in 40 cross section; the greatest external diameter being smaller than the internal diameter of the flue for which it is intended. The longitudinal outline of this body may be of any desired shape, but as shown in Figures 45 1 and 2, the same is comparatively wide at its center and converges toward its ends. Secured to the rear or inlet end of the cleaner body by a screw connection is a pipe 11 for the purpose of conducting the 50 steam or similar pressure medium to said body. As is customary, this pipe is connected at its opposite end to a hose, not shown, which communicates with the source of steam supply.

55 Extending lengthwise of the outer face of the body 10 are a plurality of spaced

spirally disposed ribs, wings or flanges 12 which gradually decrease in height from a point substantially midway of their length to the front end of said body, the front ends of said flanges meeting flush with the front end of the body. This construction facilitates entrance of the cleaner into the boiler tube. Adjacent their rear ends these ribs are provided with inwardly facing shoulders 13 which limit the extent to which the body may be inserted in the pipe. As shown in Figure 1, the spiral flanges 12 serve to properly support and center the cleaner body within the tube, said body fitting loosely enough within the latter to permit oscillatory movement thereof, and yet prevent its hammering when under steam pressure. Between these flanges and the interior of the tube spiral air passages are 75 formed, which communicate at their rear ends with the atmosphere and at their front ends with said tube. It will be noted that when the body of the cleaners is in position in the end of a boiler flue, as shown in Fig. 1, the spiral flanges 12 thereof are arranged wholly within the flue and do not extend outwardly therefrom, the shoulders 13 formed at the ends of said flanges locating the cleaner in its proper position in 80 the flue. The portions of said flanges, extending forwardly from the stop shoulders to a point substantially midway of their length, are substantially parallel with the inner wall of the tube, whereby practically 85 enclosed air channels are formed between the flanges, the body of the cleaner and the inner wall of the flue, thereby positively directing the incoming air in a spiral course through the tube.

Arranged in the front end of the body 10 is a nozzle 14 of conical form, the major portion of which projects beyond the corresponding end of said body. This nozzle is preferably removably secured to the 100 cleaner body and for this purpose is provided with a screw stem 15, suitably secured thereto, which is adapted to engage a correspondingly threaded opening 16 in a bridge piece 17 extending diametrically 105 across the interior of the body 10. The rear end of this nozzle is provided with a reduced cylindrical base portion 18 which engages a corresponding opening 19 in the front or outlet end of the cleaner body and 110 normally bears at its rear end against an inwardly projecting annular shoulder 20

provided at the base of said opening 19, as shown in Figure 2. The base of the conical end of the nozzle is preferably flush with the opposing end of the cleaner head so that there are no projecting edges to interfere with the ready insertion of the cleaner in the pipe.

Extending forwardly and outwardly through the nozzle 14 are a plurality of jet openings 21 which are equidistant apart, there being four of such openings shown in the drawings, although any number may be employed. As shown in Figure 2, these jet openings are oblique to the longitudinal axis of the cleaner body. The inlet ends of these openings are preferably chamfered or beveled as shown at 22, in Figures 2 and 6, while the outlet ends thereof are flared outwardly as shown at 23. The rear ends 20 of the jet openings 21 communicate with the interior of the body 10, while the front ends thereof are adapted to communicate with the flue pipe to be cleaned. As shown in Figures 1 and 3, the outlet ends of the 25 jet openings 21 are preferably in alinement with the air passages formed between the spiral flanges 12 of the cleaner body, whereby the incoming air comes into intimate contact with the steam emerging from said 30 jet openings.

In using my improved flue cleaner the pipe 11 is connected to a source of steam supply and allowed to escape through the nozzle for a time to permit heating of the 35 cleaner body and prevent condensation of the steam therein, after which it is placed in the boiler tube to be cleaned. The steam escapes through the jet openings 21 of the nozzle at a high velocity and is directed 40 against the inner wall of the tube, the jets of steam traveling in a rifled course through the length of the tube and effectively removing soot and scale from the walls thereof and blowing the same out at 45 its opposite end. The high pressure steam thus entering the tube produces a vacuum in rear of the nozzle 14, causing the air from the atmosphere to be drawn through the spiral passages formed between the 50 flanges 12 and correspondingly imparting a whirling or cyclonic action to the jets of steam issuing from the jet openings. Upon slightly rotating the cleaner from time to time, the paths of the steam jets are changed 55 to insure a thorough cleaning of the whole pipe.

The jet openings of the nozzle 14 are inclined in the same direction as are the spiral ribs 12 of the cleaner body 10, so that 60 the paths or courses of air and steam are in corresponding directions. Likewise the threads on the attaching stem 15 of the nozzle are of a corresponding pitch so that when the steam enters the jets of said nozzle, its tendency is to keep the latter 65

against the shoulder 20 of the body 10, and thereby prevent the same from working loose and being blown out.

By providing the cleaner body with a detachable nozzle it can readily be replaced by a new one when the same becomes worn from continued use, without the necessity of renewing the whole cleaner, thereby materially reducing the maintenance cost of such cleaners to a minimum.

It is to be understood that various changes in the form and arrangement of parts may be made without departing from the spirit of the invention.

I claim as my invention:

1. A boiler tube cleaner comprising a hollow body, spiral flanges arranged in spaced relation on the outer face of said body, and a nozzle arranged at the front end of said body and provided with a plurality of forwardly diverging jet openings for the passage of the cleaning medium therethrough, the outlet ends of said openings being flared and located in the sides of said nozzle and immediately in front of the spaces between said flanges.

2. A boiler tube cleaner comprising a hollow body, spaced spiral flanges arranged on the outer face of said body, and a nozzle arranged at the front end of said body and provided with a plurality of jet openings, the outlet ends of said openings being in substantial alinement with the spaces between said spiral flanges and in the sides of said nozzle immediately in front of said spaces.

3. A boiler tube cleaner comprising a hollow body having a bridge piece extending across the interior thereof and provided with a threaded opening, a plurality of spaced spiral flanges arranged on the outer face of said body, and a detachable nozzle extending beyond said body and provided with jet openings and a screw stem adapted to engage the opening in said bridge piece, 105 said jet openings extending lengthwise through said nozzle with their outlet ends arranged in line with the spaces formed between said spiral flanges.

4. A boiler tube cleaner comprising a hollow open-ended body having an internal shoulder and a bridge piece extending across the interior thereof in rear of said shoulder and provided with a threaded opening, a plurality of spiral flanges arranged on the outer face of said body, and a detachable nozzle having a cylindrical rear portion and a conical front portion extending beyond said body, said rear portion engaging the corresponding opening in the front end of said body and bearing against the internal shoulder of the latter, and a screw stem extending rearwardly from said nozzle and engaging the opening in said bridge piece.

5. A boiler tube cleaner comprising a hollow cylindrical body, said body being comparatively wide at its center and converging toward its ends, spiral flanges arranged in spaced relation on the outer face of said body and decreasing in height from a point substantially midway of their length to the front end of the body, said flanges being provided adjacent their rear ends
10 with forwardly facing stop shoulders, a nozzle detachably mounted in the front end of said body and having a conical front

portion, said nozzle having forwardly diverging jet openings whose outlet ends are flared and located in the sides of said conical portion immediately in front of the spaces between said spiral flanges. 15

Signed at Buffalo, in the county of Erie and State of New York, this 31st day of October A. D. 1919.

JOHN H. GOODFELLOW.
